(57) **CLAIM**

The ornamental design for the panel door and frame, as shown and described.

DESCRIPTION

FIG. 1 is a front left perspective drawing of a panel door and frame with the door closed and latched.

FIG. 2 is a front view of a panel door and frame.

FIG. 3 is a back view of a panel door and frame.

FIG. 4 is a view of one side of a panel door and frame.

FIG. 5 is view of the opposite side of a panel door and frame.

FIG. 6 is a top view of a panel door and frame; and,

FIG. 7 is a bottom view of a panel door and frame.

Portions of the drawings shown in broken lines indicate surrounding structure and environment form no part of the claimed design.
